UNITED STATES PATENT OFFICE.

RALPH A. MOWREY, OF RIDGWAY, PENNSYLVANIA.

DISPENSING-CAN.

1,079,793.

Specification of Letters Patent. Patented Nov. 25, 1913.

Application filed February 27, 1913. Serial No. 751,126.

To all whom it may concern:

Be it known that I, RALPH A. MOWREY, a citizen of the United States, residing at Ridgway, in the county of Elk, State of Pennsylvania, have invented certain new and useful Improvements in Dispensing-Cans; and I do hereby declare the following to be a full, clear, and exact description of the invention, such as will enable others skilled in the art to which it appertains to make and use the same.

This invention is directed to improvements in dispensing cans, and particularly to one used for dispensing cream.

15 The invention has for its object to provide a device of this character having mounted therein an agitator which will thoroughly mix the cream each time the turning plug is operated to draw cream from the can.

20 With these and other objects in view, this invention resides in the novel features of construction, formation, combination and arrangement of parts to be hereinafter more 25 fully described, claimed and illustrated in the accompanying drawing, in which:—

Figure 1 is a side elevation of the device. Fig. 2 is a top plan view. Fig. 3 is a vertical sectional view through the device. Fig. 30 4 is a vertical central sectional view. Fig. 5 is a sectional view on line 5—5 of Fig. 3. Fig. 6 is a sectional view on line 6—6 of Fig. 1.

Referring to the drawing, the numeral 1 35 designates a can, the same being preferably circular in cross section and has formed in its bottom 2 a socket 3 in which is rotatably mounted the lower end of the agitator shaft 4. Carried by the agitator shaft 4 is a 40 spiral blade 5, whereby when the shaft 4 is rotated the blade 5 thoroughly mixes or agitates the cream contained in the can.

A hollow cover 6 is provided for the can and has secured therein a bar 7, one end of 45 which is provided with a flange 8 similar to the flange 9 which is connected to the strip intermediate its ends, said flanges being adapted to fit into the upper end of the can 1 to hold the cover 6 in place thereon.

50 Mounted upon the strip 7 is a pair of spaced brackets 10, in which is journaled a horizontal shaft 11, the inner end of which has fixed thereto a beveled gear 12, which meshes with a similar gear 13 fixed to the upper end of the shaft 4. The upper end of the shaft 4 is journaled in the strip 7, thus

holding the same in its proper position within the can 1.

Journalized in a suitable stuffing box 14 mounted upon the strip 7, and adjacent the outermost bracket 10 is a shaft 15, the lower end of which is provided with a socket 16. Fixed to the upper end of the shaft 15 is a beveled gear 17 which meshes with a similar gear 18 fixed to the outer end of the shaft 11. 65

Mounted upon the side of the can 1 is a pair of spaced brackets 19, in the lowermost one is journaled the lower end of a vertical shaft 20, said shaft having its upper end journaled in the uppermost bracket 19 70 and engages in the socket 16, whereby when the cover 6 is removed from the can 1 the socket 16 readily disengages the upper end of the shaft 20.

Connected to the lower end of the can 1 75 is a cock 21 having mounted therein a turning plug 22 which is provided with a stem 23, said stem passing through a barrel 21 carried by the cock. The upper end of the stem 23 is journaled in the upper end of the 80 barrel 24 and has fixed thereto a beveled pinion 25 which meshes with a similar pinion 26 carried by the shaft 27, said shaft being journaled in the uprights 28 carried by the upper end of the barrel 24. The outer end 85 of the shaft 27 is provided with a handle 29, said shaft also having fixed thereto a gear 30, which meshes with a gear 31 fixed to the lower end of the shaft 20. From this construction it will be seen that upon rotation of 90 the handle 29 the shaft 23 is rotated, which operates the turning plug 22 so that a quantity of the milk will pass through the cock 21. When the handle 29 is rotated corresponding movement is imparted to the shaft 95 27 which rotates the gear 30, and through the medium of the shaft 20 the shaft 11 is rotated, which in turn rotates the agitator shaft 4 so that the spiral blade carried thereby will rotate, thus thoroughly mixing the 100 milk and cream upon each operation of the handle 29.

The can is especially adapted for use in lunch rooms so that the cream which naturally rises to the top of the milk is thoroughly mixed with the milk so that the customer is sure of getting a rich glass of milk. 105

What is claimed is:—

In combination with a can having an agitator mounted therein, of a cock connected to 110 the can, a turning plug for the cock, a barrel carried by the cock, a horizontal shaft jour-

naled upon the upper end of the barrel, a handle carried by the shaft, a stem having its lower end connected to the turning plug and its upper end provided with a gear adapted 5 to mesh with a gear carried upon said shaft, a vertical shaft journaled upon the side of the can, and having its lower end provided with a gear adapted to mesh with a gear fixed to the horizontal shaft, a second vertical shaft having a socket formed upon its lower end adapted to detachably connect the first named vertical shaft, a cover having

journaled therein a horizontal shaft and means connecting the second named vertical shaft and second named horizontal shaft for 15 rotating the agitator when the handle and turning plug are rotated.

In testimony whereof, I affix my signature, in the presence of two witnesses.

RALPH A. MOWREY.
